UNITED STATES PATENT OFFICE.

CLARENCE A. BAKER, OF PHOENIX MILLS, NEW YORK.

CROSS-LINE BUCKLE.

No. 821,976.

Specification of Letters Patent.

Patented May 29, 1906.

Application filed June 3, 1905. Serial No. 263,618.

To all whom it may concern:

Be it known that I, CLARENCE A. BAKER, a citizen of the United States, residing at Phoenix Mills, in the county of Otsego and State 5 of New York, have invented certain new and useful Improvements in Cross-Line Buckles, of which the following is a specification.

This invention relates to improvements in cross-line buckles; and it consists, essentially, 10 of a buckle-framework adapted to be placed upon the long line and a link to which the cross-line is attached and which is detachably connected to one of the cross-bars.

It has for its object to produce a device of 15 this character which will enable the cross-line to be quickly and easily detached from or adjusted to any desired point on the long line, which will be simple and durable in construction, and which can be cheaply manufactured and placed upon the market.

For a full description of the invention and the merits thereof and also to acquire a 20 knowledge of the details of construction of the means for effecting the result reference 25 is to be had to the following description and accompanying drawings, in which—

Figure 1 is a detail perspective view showing the parts of the buckle in position. Fig. 2 is a longitudinal sectional view showing the 30 straps in position. Fig. 3 is a perspective view, partly in section, of the link and the intermediate cross-bar. Fig. 4 is a plan view of the link member. Fig. 5 is a longitudinal 35 sectional view showing a modification in which the ends of the side pieces are curved upward to allow the long line to pass through the buckle in a straight line.

Corresponding and like parts are referred to in the following description and indicated 40 in all the views of the drawings by the same reference characters.

The frame of the buckle comprises the usual side pieces 1, which are connected by end bars 2 and an intermediate cross-bar 3, the latter being provided with a stud 4 on 45 one side and a hook 5 on the opposite side. It will be observed that there is a space 11 between the side pieces 1 and the ends of the hook 5 and that the sides 12 of the hook are 50 curved so that the space between their ends or the mouth of the hook is not as large as the diameter of the opening through the

hook. A link 6 is used in connection with this frame and is of such a width as to fit loosely between the side pieces 1. One of the 55 ends 7 of the link is of such a size as to fit within the opening through the hook 5, and a notch 8 is formed in a side of the link and adjacent the end 7, so that the link can be slipped into position from the side of the 60 frame when it is turned so that the notch 8 will fit into the mouth of the hook. After the link has been inserted, as above described and turned around into the opposite and normal direction it will be readily 65 understood that same cannot be removed. In the preferred construction of the link 6 the end 13, to which the cross-line 9 is attached, is disposed obliquely with respect to the opposite end 7, as best seen in Fig. 4. 70

In operation the long line or hand-rein 10 is passed through the framework of the buckle, and after same has been adjusted to the desired position the stud 4 is allowed to engage an opening therein. The link 6, to 75 which the cross-line is attached, can be quickly removed or placed in position by turning it back so that it extends in an opposite direction to that which it normally has and then either sliding it out or placing it in position from a side of the frame. By the use 80 of this device a set of double reins can be quickly changed to a set of single reins by detaching the link and securing a line thereto. 85

In the preferred form, as shown in Fig. 5, the ends of the side pieces are curved upward. This permits the long line to pass through the buckle in a straight line, and hence greatly facilitates adjustment. 90

Having thus described the invention, what is claimed as new is—

1. In a cross-line buckle, the combination of a frame comprising side pieces, end bars, and an intermediate cross-bar having a stud 95 upon one side and a hook upon the opposite side, said hook having a mouth smaller than the diameter of the opening therethrough and the before-mentioned side pieces being curved to allow the long line to pass through the buckle without bending, and a link one end of which is of such a size as to fit in the opening through the hook, one of the sides of the link being notched at a point adjacent

said end so that it can be slipped into the hook from the side and cannot be disengaged when turned in the opposite direction.

2. In a cross-line buckle, the combination
5 of a frame comprising side pieces and connecting cross-bars, an intermediate cross-bar being provided with a stud upon one side and a hook upon the opposite side, and a link

which is detachably connected to the frame by the above-mentioned hook.

In testimony whereof I affix my signature in presence of two witnesses.

CLARENCE A. BAKER. [L. s.]
